(57) **CLAIM**

The ornamental design for a magnifying glass with light, as shown and described.

DESCRIPTION

FIG. 1 is a perspective view of a first embodiment of a magnifying glass with light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the magnifying glass with light where the magnifying glass with light is in a configuration of use;

FIG. 10 is an enlarged view of portion 10 shown in FIG. 1;

FIG. 11 is a perspective view of a second embodiment of a magnifying glass with light showing my new design;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a perspective view of the magnifying glass with light where the magnifying glass with light is in a configuration of use; and,

FIG. 20 is an enlarged view of portion 20 shown in FIG. 11.

The dash-dash broken lines in the drawings depict portions of the magnifying glass with light and form no part of the claimed design. The additional dash-dash broken lines in FIGS. 9 and 19 show portions of the environment and form no part of the claimed design. The dot-dash broken lines represent boundaries of the enlarged portions and form no part of the claimed design.

1 Claim, 20 Drawing Sheets
